UNITED STATES PATENT OFFICE.

DWIGHT D. KING, OF HOT SPRINGS, ARKANSAS.

DESIGN FOR A VEHICLE-LAMP.

51,901.

Specification for Design.

Patented Mar. 26, 1918.

Application filed December 1, 1917. Serial No. 204,986. Term of patent 14 years.

To all whom it may concern:

Be it known that I, DWIGHT D. KING, a citizen of the United States, residing at Hot Springs, in the county of Garland and State of Arkansas, have invented a new, original, and ornamental Design for Vehicle-Lamps, of which the following is a specification, reference being had to the accompanying drawings, forming a part thereof.

Figure 1 is a view in front elevation showing my new design,

Fig. 2 is an inverted plan view of Fig. 1, Fig. 3 is a rear elevation of Fig. 1, and Fig. 4 is a side elevation of Fig. 1.

I claim:

The ornamental design for a vehicle lamp, as shown.

DWIGHT D. KING.

Witnesses:

E. I. GROOM,
STONLEY LEE.
